LUBRICATOR FOR INTERNAL COMBUSTION ENGINES

Application filed November 7, 1930. Serial No. 494,140.

This invention relates to lubricating devices especially designed for use in connection with internal combustion engines for the purpose of lubricating the cylinder walls, 5 pistons and valves of such engines.

The invention has for an object to provide an improved lubricator embodying means to draw oil from a reservoir, and deliver it in a finely divided vesicular condition as a spray into the engine via the intake manifold.

Further, the invention has for an object to provide a means by which the lubricant may be drawn into the engine cylinders under 15 a very low vacuum.

Further, it is an object to provide a lubricator having sight feed features whereby the operator may at all times observe the operation and make such adjustments from time 20 to time as may be necessary in order to obtain the most efficient results.

Further, it is an object to provide a lubricator in which the air inlet ports are protected against dirt and clogging and against 25 exposure.

Further, it is an object to provide means whereby the oil is drawn into a duct and there converted from a liquid into a continuous stream of air-in-oil bubbles and 30 thereafter treated with an additional quantity of air to burst the bubbles and dissipate the oil of the films into exceedingly fine particles as a vapor before delivering the same to the engine.

Further, the invention has for an object to provide a lubricator of such construction and arrangement of parts that the spray of the fine vesicular mixture of oil and air is swept into the intake pipe and thus reaches 35 the combustion chambers, piston heads and valves where it is deposited, the action being independent of the level of the free oil surface in the reservoir and is just as efficient whether the reservoir is full or nearly empty.

Further, it is an object of the invention to provide a lubricator in which there are no mechanical moving parts, and in virtue of which the lubricator will function properly at all times regardless of the period it may 40 have been in use.

Further, it is an object of the invention to provide a lubricator which will draw oil into a chamber and upon its entry convert it into vesicular bodies of air-in-oil films and then explode those bodies with additional 55 air before the resultant vapor is delivered into the engine.

Further, it is an object to provide a simple, efficient device for the purpose described that may be manufactured at nominal expense, 60 will be neat in appearance and will not require structural changes to be made in the engine system or vehicle to which it may be applied.

Other objects will in part be obvious and in 65 part be pointed out hereinafter.

To the attainment of the aforesaid objects and ends, the invention still further resides in the novel details of construction, combination and arrangement of parts, all of which 70 will be first fully described in the following detailed description, then be particularly pointed out in the appended claims, reference being had to the accompanying drawings, in which:—

Figure 1 is a diagrammatic view showing the relation of the oil reservoir and the intake manifold to the lubricator proper.

Figure 2 is a perspective view of the lubricator proper.

Figure 3 is an enlarged front elevation and part vertical section taken on the line 3—3 of Figure 4.

Figure 4 is a side elevation of the lubricator proper.

Figure 5 is a horizontal section on the line 5—5 of Figure 3.

Figure 6 is a vertical section on the line 6—6 of Figure 3.

Figure 7 is a perspective view of the removable plug.

Figure 8 is a perspective view of the inlet elbow.

Figure 9 is a perspective view of the outlet elbow, showing the tiny outlet hole.

In the drawings, in which like numerals of reference indicate like parts in all of the figures, 1 represents the lubricator proper which consists of a body having a base 2 and a head 3 connected by an intermediate part 4,

the latter having its front portion removed to expose a groove 5 that extends into the head and base. The head is provided with an outlet duct comprising the receiving end 6, with 6 a narrow passage 8, and a delivery end 7, the latter being somewhat in the form of a chamber and the head is tapped so that an elbow 31 may be screwed into the head, the elbow 31 having a minute entrance aperture 32 to register with the chambered portion 7 of the outlet duct of the head 3. The suction duct 33 from the intake manifold of the engine is connected with the elbow 31.

9 is a drill hole which extends into the 15 head and has its entrant end plugged as at 10. The drill hole 9 communicates with the duct portion 7 through a valved passage 11 controlled by a needle valve 13 that is threaded into the head 3 and is provided with a lock 20 nut 15 and a turning head 14 as indicated, the needle valve 13 being threaded at 12 into the head 3.

16 is a small air port communicating with the drill hole 9 and with the atmosphere at a 25 point within the groove 5 in back of the sight glass tube 35 that is held in the groove 5 but spaced slightly from the wall thereof. The port 16 may be formed by drilling through the head and intersecting the drill hole 9 and 30 later plugging the outer portion of the drill hole as at 17, or it may be drilled from the groove end directly into the drill hole 9 as may be found convenient.

The head 3 has a seat 18 against which the 35 glass tube 35 is held in gas-tight engagement in a manner presently explained, there being a suitable felt washer 36 interposed between the seat 18 and the end of the tube 35 as shown.

40 The base part 2 is drilled and tapped as at 19 to receive a removable screw plug 20, the latter having an annular air space or groove 21 and also being provided with a seat 22 for the tube 35, a felt washer 36 being interposed 45 between that seat and the adjacent end of the tube. By screwing the plug 20 tightly into the base 2 the tube 35 is held rigidly in position and sealed against leakage of air and oil.

50 The plug 20 is also provided with a cup-like portion 23 into the bottom of which the inlet end 24 of the oil duct 24-25 deliver oil from the elbow 26 that is screwed into the base 2 and into the plug 20, thus locking the plug against coming unscrewed.

The elbow 26 has its end 27 provided with a coupling 28 to the pipe 29 that extends into the supply tank 30, the latter being located at any convenient place.

60 It is to be observed that the opening through the elbow 26 that delivers the oil into the entrance portion 25 of the intake duct 24-25 is of relatively considerable cross sectional area, it not being necessary to restrict this opening in the elbow. However, the out-

let opening 32 through the elbow 31 is preferably considerably restricted.

37 is an air duct in the base 2, the entrant end of which is drilled from the groove 5 so as to lie behind the glass tube 35, while the delivery end of the duct 37 communicates with the air space 21. The plug 20 has a restricted air passage 38 from the air space 21 into the recess 23 of the plug so that a limited amount of air may be drawn into the tube 35 to assist in the formation of bubbles or air encased in thin films of oil. 70 75

In the operation of the device the valve 13 is so adjusted that just the right amount of vaporized oil is delivered to the engine. 80 When the engine is running the suction causes the oil to be drawn into the glass tube 35 via the parts 29, 28, 27, 26, 25, 24 and 23 at the same time air is sucked into the bottom of the tube 35 through the passage 38 and caused 85 to act upon the oil so as to transform the oil column into a column of bubbles or froth, this column of bubbles or froth extending from the top of the oil column (which oil column seldom reaches above the top of the base 2) 90 to the head 3. The oil bubbles then passing through the restricted portion of the outlet duct 8 into the enlarged area 7 where they encounter additional air via the port 11 and are exploded or burst, thereby distributing 95 the oil particles of the film throughout the air within the space and in effect carburetting it. The air particles at this time are so tiny that the stream of material passing through the suction line 33 into the intake manifold 100 is in the form of an exceedingly light vapor, the oil being in an exceedingly finely atomized state.

From the foregoing description, taken in connection with the accompanying drawings, 105 it is thought the complete construction, operation and advantages of the invention will be understood by those skilled in the art, and it will be further understood that slight changes in the details of construction, arrangement and design of parts may be made 110 without departing from the spirit of the invention or the scope of the appended claims.

What is claimed is:

1. A lubricator comprising a body having a recess with a seat at its top end, a transparent tube held in said recess with its top end sealed against said seat, said body having a passage through its lower end registering with the lower end of said recess, a plug held in 120 said passage and itself having a seat sealed against the lower end of said tube, a suction duct communicating at one end with the upper end of said tube and at the other end with a source of suction, valve controlled 125 means to admit air to said body at a location between said suction duct and its place of communication with the upper end of said tube, means to pass oil to said tube through said plug, means to pass a restricted volume 130

of air into said tube through said plug, and a duct from a source of oil supply to said body and plug.

2. A lubricator comprising a body having a base portion, a head portion and an intermediate part, the latter having an exposed groove, said base and said head portions having provisions to receive a tube, and said base portion having a passage through which the tube may be inserted, a tube held in said groove, a plug closing said passage, said head portion having a seat for the upper end of said tube, and said plug having a seat for the lower end of said tube, said plug having an oil inlet passage to said tube, means conveying oil from a source to said oil inlet passage, said head having an outlet passage communicating at one end with said tube and at its other end with a suction means, said plug having an air space between itself and said base, said body having an air duct from said groove to said air space, said plug having a restricted port between said air space and the interior of said tube, and controlled means in communication with said outlet passage for admitting air thereto, said tube serving to protect the entrance of said air ducts from solid matter.

3. A lubricator comprising a body having a base portion, a head portion and an intermediate part, the latter having an exposed groove, said base and said head portions having provisions to receive a tube, and said base portion having a passage through which the tube may be inserted, a tube held in said groove, plug closing said passage, said head portion having a seat for the upper end of said tube, and said plug having a seat for the lower end of said tube, said plug having an oil inlet passage to said tube, means conveying oil from a source to said oil inlet passage, said head having an outlet passage communicating at one end with said tube and at its other end with a suction means, said plug having an air space between itself and said base, said body having an air duct from said groove to said air space, said plug having a restricted port between said air space and the interior of said tube, controlled means in communication with said outlet passage for admitting air thereto, said controlled means comprising an air duct in said head from said groove to said outlet passage, and a needle valve in said head to control the area of said air duct.

4. A lubricator comprising a body having a base portion, a head portion and an intermediate part, the latter having an exposed groove, said base and said head portions having provisions to receive a tube, and said base portion having a passage through which the tube may be inserted, a tube held in said groove, a plug closing said passage, said head portion having a seat for the upper end of said tube, and said plug having a seat for the lower end of said tube, said plug having an oil inlet passage to said tube, means con-

veying oil from a source to said oil inlet passage, said head having an outlet passage communicating at one end with said tube and at its other end with a suction means, said plug having an air space between itself and said base, said body having an air duct from said groove to said air space, said plug having a restricted port between said air space and the interior of said tube, and controlled means in communication with said outlet passage for admitting air thereto, said tube serving to protect the entrance of said air ducts from solid matter.

5. In lubricators, a body having a head portion, a base portion and an intermediate portion, the latter having an open sided grooved face, a glass tube located in the groove of said face but out of contact therewith, said head having a seat for said glass tube and having a discharge duct to effect communication between said glass tube and a source of suction, said base having a passage for said tube, a plug closing said passage and having a seat for said glass tube and adapted to hold said glass tube seated, said plug and said base having an oil inlet passage communicating with said glass tube, a tubular member screwed into said base and plug inlet passages and adapted for communication with a source of oil supply, said base having an air duct from said groove behind said glass tube to said plug, said plug having a restricted air port from said air duct to said glass tube, said head having an air inlet from said groove behind said glass tube to said discharge duct, and a valve in said head to control the passage of air to said discharge duct.
